LEONARD ARTHUR DIXON AND JAMES BARCLAY PEAT, OF MIDDLESBROUGH,
ENGLAND

BOAT RAISING AND LOWERING GEAR

Application filed February 8, 1930, Serial No. 426,849, and in Great Britain May 3, 1929.

This invention is for improvements in or relating to raising and lowering gear for ships' boats, which gear is of the type comprising davit-arms constructed to move outboard automatically under the weight of the boat when they are released. Such davits may be controlled either by the falls for the boat, or by separate ropes or cables, and one object of the invention is to improve the construction of gear of this type with a view to obtaining a more efficient application of the power required to house the davit-arms and the boat.

The invention accordingly comprises a boat-raising and lowering gear of the type described wherein the davit-arm carries a movable fulcrum arranged to travel in one path (for example, a path inclined downwardly and outwardly to the side of the ship), and the lower end of the davit-arm is constrained to move in another dissimilar path, said paths being so arranged as to cause a simultaneous lowering and outboard turning movement of the head of the davit-arm when the davit-arm is released.

According to another feature of this invention, the path aforesaid of the lower end of the davit-arm slopes downwardly and outwardly from the inner end, and is thereafter curved inwardly from the side of the ship to terminate in a substantially horizontal portion. This shaping gives an automatic lock which holds the davit-arm in its out-turned position against accidental inboard movement.

According to a further feature of the invention, a multiple purchase system of pulleys and tackle is provided for controlling the davit-arm. If desired, the boat and the davit-arm may be controlled respectively by two independent systems of pulleys and tackle, for instance of different purchase.

For a more complete understanding of the invention, four embodiments thereof will now be described by way of examples with reference to the accompanying drawings which are of a diagrammatic character. In the drawings,

Figure 1 is a side elevation of one construction, and

Figures 2, 3 and 4 are similar views of separate modifications.

Like reference numerals indicate like parts in the various figures of the drawings.

In the construction shown in Figure 1, 55 there is provided a davit-stand 10 comprising two track-members 11 which are spaced apart in plan. Each of these track-members has a horizontal portion 12 situated above the deck of the ship and supported by stand- 60 ards 13 or secured to the engine casing or other structure as may be convenient. This horizontal portion merges into an inclined portion 14 which slopes downwardly and outwardly to the side of the ship, and termi- 65 nates in a substantially vertical portion 15 which is fixed at its lower end to the deck of the ship.

A davit-arm 16 is mounted between the two track-members 11 which davit-arm is 70 curved outwardly at its upper end towards the side of the ship and has at its lower end a substantially straight portion. Near the inner end of said straight portion the davit-arm is provided with a movable fulcrum or 75 main bearing in the form of rollers 17 arranged one on each side of the davit-arm, and to run on the inclined portion 14 of the track-members. The lower end of the davit-arm has a rearwardly extending projection on which 80 two rollers 18 are mounted. The said rollers are received and adapted to travel in a curved track 19 provided on plates or brackets 20 on the davit-stand 10. The track 19 is shaped so as to provide a straight or substantially 85 straight, portion 21 which is inclined downwardly at a small angle to the inclined portion 14 of the track-members 11. This inclined portion of the track 19 slopes outwardly towards the side of the ship and is 90 thereafter curved inwardly as shown at 22 and finally terminates in a substantially horizontal portion 23. This shaping of the lower end of the track 19 gives an automatic locking 95 which holds the davit-arm in its outboard position against accidental inboard movement.

The boat and the davit-arm are both controlled by a single cable 24 which is led from a winch or other hoisting apparatus (not shown) over a pulley 25 carried by a bracket 100

26 on the davit-stand 10. The cable extends thence substantially in the direction of the inclined portion 14 of the track-members 11 and around a pulley 27 on the davit arm 16, 5 which pulley may be adjustably mounted on the davit-arm.

From the pulley 27 the cable is led backwardly in a direction parallel, or substantially so, to the run of the cable between the pulleys 25 and 27. The cable is then led around a pulley 28 on the upper end of the bracket 26 and thence to a pulley 29 on the head of the davit-arm. The cable 24 then passes round a movable pulley 30 from which the boat 31 (indicated in chain lines) is suspended by any convenient means. The end of the cable is secured to the head of the davit-arm 32.

Any suitable locking device can be provided for holding the davit-arm in the housed or inboard position.

When the cable 24 is released, the rollers 17 constituting the movable fulcrum of the davit-arm, travel down the inclined portion 14 of the track-members 11 and during this movement the rollers 18 on the lower end of the davit-arm travel in the curved track 19. Thus a simultaneous lowering and outboard turning movement of the boat is effected until the rollers 18 reach the end of the track 19. The davit-arm then comes to rest against a stop on the davit-stand. Any convenient davit-stop may be provided; in the constructions shown on the drawings this stop takes the form of a batten 48 between the track-members 11. It will be appreciated that when the rollers 18 reach the end 23 of the track 19, a further slackening of the cable effects the lowering of the boat until it is water-borne. In this position the davit-arm is locked by the curved track 19 and the rollers are prevented from running backwardly up the inclined track 14 until a force is applied at the head of the davit-arm. When 45 a pull is exerted on the cable 24 the boat is first raised from the water until it is supported in known manner on the head of the davit-arm and then a continued pull on the cable will cause the davit-arm to be raised 50 and turned inboard.

It will be appreciated that the arrangement of pulleys and tackle described gives a double purchase for raising the boat, and that when the boat is supported by the davit-arm the double purchase is transferred to the arm for hauling it inboard. If desired, the pulley 30 may be dispensed with and the end of cable 24 be connected directly to the boat. Moreover, it will be seen that the force exerted when the davit-arm is moving inboard or outboard acts substantially in the direction of travel of the movable fulcrum, and the force controlling the turning of the davit-arm acts as a moment about the movable fulcrum. Also that there is not at any time

during the travel of the davit-arm any vertical force exerted on the rollers constituting the movable fulcrum.

The embodiment of the invention shown in Figure 2 is very similar to that illustrated in Figure 1. The cable 24 instead of passing directly from the pulley 27 to the pulley 28 is first led around pulleys 33 and 34 on the stand 26 and the davit-arm 16 respectively. This arrangement gives a quadruple purchase for raising the davit-arm. 75

Figures 3 and 4 show two constructions in which two independent systems of pulleys and tackle are employed for controlling the boat and davit-arm respectively. Referring first to the construction shown in Figure 3, the track 19 instead of being curved as shown in Figures 1 and 2 is straight, but is inclined downwardly and inwardly relatively to the side of the ship. The boat 31 can be raised or lowered by a cable 35 which is led from a winch or other hoisting mechanism (not shown) around a pulley 36 on the davit-arm 16, and thence to a six-fall pulley block system 37 whereof the upper or fixed block is secured to the head of the davit-arm and the lower or movable block is connected to the boat 31. The end of the cable 35 is fixed at 38 to the head of the davit-arm.

The davit-arm is controlled by a separate system of pulleys and tackle comprising a cable 39 which is led from any suitable winch or other hoisting mechanism (not shown). The cable 39 passes first around a pulley 40 on the davit-stand 10, thence in a direction approximately parallel to the inclined portion 14 of the track-members 11 and around a pulley 41 mounted on the davit-arm 16 coaxially with the rollers 17. From the pulley 41 the cable 39 is led backwardly in a direction parallel to the run of the cable between the pulleys 40 and 41. The cable then passes around a pulley 42 on the davit-stand, thence around a pulley 43 on the davit-arm coaxial with the pulley 36, and the end of the cable is secured at 44 to the davit-stand. It will be observed in this construction the boat is raised by a six-fall pulley block system and the davit-arm is controlled by a purchase system. 115

In the construction shown in Figure 4 the boat is raised by a six-fall pulley system as in the embodiment illustrated in Figure 3. A cable 45 and six-fall pulley block system 46 is provided for controlling the davit-arm. The fixed block of this system is mounted on the bracket 26 and the movable block is connected by a strop 47 to the davit-arm. 120

It is to be understood that the invention is not restricted to the constructional details described as any convenient arrangement of pulleys and tackle can be employed without departing from the invention. 125

We claim:—

1. In a boat raising and lowering gear of the type set forth wherein the davit-arms, on being released, move outboard automatically due to the weight of the boat, the combination with a davit-arm, one part of which carries a movable fulcrum arranged to travel in one path, of a roller carried by another part of the davit-arm and a track which is dissimilar to said path and on which said roller is arranged to travel, which track is so shaped that the vertical component of the movement of said roller is greater than the horizontal component at least during the major portion of the outboard movement of the boat.

2. In a boat raising and lowering gear of the "gravity" type wherein the davit-arms move outboard automatically under the weight of the boat when they are released, the combination with a davit-arm which carries intermediate of its ends a movable fulcrum arranged to travel in a path which is inclined downwardly and outwardly to the side of the ship, of means to constrain the lower end of the davit-arm to travel in a path which slopes downwardly and outwardly from its inner end and is thereafter curved inwardly from the side of the ship to terminate in a substantially horizontal portion, for the purpose set forth.

3. In a boat raising and lowering gear of the "gravity" type wherein the davit-arms move outboard automatically under the weight of the boat when they are released and wherein one part of each davit-arm carries a movable fulcrum arranged to travel in one path and another part of the davit-arm is constrained to move in a dissimilar path, the combination with a davit-stand, of tackle for controlling the davit-arms, which tackle includes two pulleys arranged one above the other on the davit-stand, a pulley on one davit-arm intermediate of its ends, a pulley at the head of that davit-arm, a double-purchase lifting block, and a rope which passes over the lower pulley on the davit-stand, thence around the pulley on the davit-arm which is situated between the extremities of that arm, thence around the upper pulley on the davit-stand and thence around the pulley at the head of the davit-arm and the lifting block and is finally anchored on the head of the davit-arm.

4. A boat-raising and -lowering gear of the type described, comprising a davit-arm which carries a movable fulcrum adapted to travel on a downwardly and outwardly extending track, a track extending downwardly and, for at least a portion of its length, inwardly for constraining the lower end of the davit-arm, said tracks being so arranged as to cause a simultaneous lowering and outboard turning movement of the head of the davit-arm when the davit-arm is released, and a single system of pulleys and tackle for

controlling both the boat and the davit-arm so arranged that the boat is raised by double purchase and subsequently the davit-arm is moved inboard by multiple purchase.

5. A boat-raising and -lowering gear of the type described, comprising a davit-arm which carries a movable fulcrum adapted to travel on a downwardly and outwardly extending track, a track extending downwardly, outwardly and having an inward bend for constraining the lower end of the davit-arm to move in an angular path, said tracks being so arranged as to cause a simultaneous lowering and outboard turning movement of the head of the davit-arm when the davit-arm is released, and a system of pulleys and tackle for controlling the boat and the davit-arm respectively.

6. A boat-raising and -lowering gear of the type described, comprising a davit arm which carries a movable fulcrum arranged to travel an outwardly inclined track, an inwardly inclined track constraining the lower end of the davit-arm, said tracks being so arranged as to cause a simultaneous lowering and outboard turning movement of the head of the davit-arm when the davit-arm is released, and two independent systems of pulleys and tackle of different purchase for controlling the boat and the davit-arm respectively.

7. A boat-raising and -lowering gear of the type described, comprising a davit-arm which carries a movable fulcrum arranged to travel down a sloping track, a track having at least a portion thereof sloping inwardly constraining the lower end of the davit-arm, said tracks being so arranged as to cause a simultaneous lowering and outboard turning movement of the head of the davit-arm when the davit-arm is released, a six-fall pulley-block system for raising the boat, and a quadruple system of pulleys and tackle for controlling the davit-arm.

8. A boat-raising and -lowering gear of the type described, comprising a davit-arm which carries a movable fulcrum arranged to travel down an outwardly inclined track, an inwardly inclined track for guiding the lower end of the davit-arm downwardly, said tracks being so arranged as to cause a simultaneous lowering and outboard turning movement of the head of the davit-arm when the davit-arm is released, and two six-fall pulley-block systems for raising the boat and controlling the davit-arm respectively.

9. In a boat-raising and lowering gear of the type described, the combination of a davit-arm, a roller which constitutes a movable fulcrum journalled in the davit-arm and arranged to travel on a downwardly and outwardly extending track, a downwardly and inwardly extending track guiding the lower end of the davit-arm, said tracks being so arranged as to cause a simultaneous lowering

and outboard turning movement of the head of the davit-arm when the davit-arm is released, and a multiple purchase system of pulleys and tackle for controlling the davit-arm.

10. In a boat launching and stowing apparatus, a davit-arm having rollers journaled therein adjacent its central portion and lower end, an outwardly inclined track for the former and a track having at least a portion thereof inclined inwardly for guiding the latter, which tracks are arranged to cause a simultaneous outboard turning movement and lowering of the head of the davit-arm when the davit-arm is released.

11. In a boat launching and stowing apparatus, a davit-arm, track-engaging means on the davit-arm adjacent its central portion and lower end, an outwardly inclined track for the former and a track having at least a portion thereof inclined inwardly for guiding the latter, which tracks are arranged to cause a simultaneous outboard turning movement and lowering of the head of the davit-arm when the davit-arm is released.

In testimony whereof we have signed our names to the specification.

LEONARD ARTHUR DIXON.
JAMES BARCLAY PEAT.
